UNITED STATES PATENT OFFICE

152,131

DESIGN FOR A PARALLEL VISE AND CLAMP

Dell Wright, Elgin, Ill.

Application March 18, 1946, Serial No. 127,638

Term of patent 14 years

(Cl. D54—13)

To all whom it may concern:

Be it known that I, Dell Wright, a citizen of the United States, residing at Elgin, in the county of Kane and State of Illinois, residing at 21 North Commonwealth Avenue, Elgin, Illinois, have invented a new, original, and ornamental Design for a Parallel Vise and Clamp, of which the following is a specification, reference being had to the accompanying drawings, forming a part thereof.

In the drawings:

Fig. 1 is a plan view showing my ornamental design;

Fig. 2 is a side elevational view thereof; and
Fig. 3 is a front view.

I claim:

The ornamental design for a parallel vise and clamp, as shown.

DELL WRIGHT.
